UNITED STATES PATENT OFFICE.

AUDY A. LOWRY, OF ANNA, ILLINOIS, ASSIGNOR OF ONE-HALF TO CALEB M. MILLER, OF ANNA, ILLINOIS.

THRESHING-MACHINE.

SPECIFICATION forming part of Letters Patent No. 733,231, dated July 7, 1903.

Application filed May 31, 1902. Serial No. 109,745. (No model.)

To all whom it may concern:

Be it known that I, AUDY A. LOWRY, a citizen of the United States, residing at Anna, in the county of Union and State of Illinois, have 5 invented a new and useful Threshing-Machine, of which the following is a specification.

This invention relates to self-propelling threshing-machines; and it has for its object 10 to provide certain improvements within the scope of the device which shall possess superior advantages in point of simplicity, durability, and general efficiency.

With these ends in view the invention consists in the improved construction, arrangement, and combination of parts, which will 15 be hereinafter fully described, and particularly pointed out in the claims.

In the accompanying drawings, Figure 1 is a side elevation of a threshing-machine constructed in accordance with the principles of 20 my invention. Fig. 2 is a longitudinal sectional view in detail, showing the construction of the casing of the chaffing fan or blower, its relation to the shoe which carries the chaffing-riddle, and also showing the construction 25 of the conveyers to deliver the grain from the machine and discharge the same into sacks or other receptacles. Fig. 3 is a vertical transverse sectional view taken on a plane indicated by the line *b b* in Fig. 2.

My invention has special reference to that class of threshing-machines which are equipped with an engine which may be used 30 for the purpose of transporting the threshing-machine from one place to another by connecting suitable traction-gearing, which forms part of the machine, with the drive-shaft of the engine, and which also when the machine has reached the scene of operation 35 may be utilized for driving the threshing mechanism. These parts of the device are not intended to be claimed in the present application and have only been partly shown in Fig. 1 of the drawings, which has been introduced only for the purpose of showing certain parts relating to my present invention. The latter may be described as consisting, 40 essentially, in the improved construction of the casing of the chaffing fan or blower in its relation to the shoe which carries the chaffing-riddle and in the construction of certain

conveyers whereby the cleaned grain is discharged from the machine into suitable receptacles.

Referring now to the drawings, 1 designates 55 the supporting-easing of the machine, which is mounted upon front wheels 2 and rear wheels 3, the latter constituting the traction-wheels.

The general construction of the threshing-machine is well understood, it differing in no essential particular from threshing machinery of ordinary construction, being provided with a cylinder, of which 62 designates the shaft, and with a blower-fan 118, (best seen 65 in Fig. 2,) of which 117 designates the shaft, which is provided with a pulley 119, connected by a belt 120 with a pulley 121 upon the cylinder-shaft.

59 designates the fly-wheel, mounted upon 70 the shaft 30 of the driving-engine, which latter does not appear in the drawings, but from which motion is to be transmitted to the operating parts of the device.

The shoe 122, which carries the chaffing- 75 screen 123, is mounted for lateral vibration by the usual means and is vibrated by the mechanism commonly employed for that purpose, which mechanism is not shown nor described herein, as the same is well understood 80 by those skilled in the art to which my invention relates and forms no part of my present improvements. The casing 124, in which the blower-fan 118 is inclosed, has its lower side inclined upwardly and rearwardly, as at 125, 85 and adapted to direct the blast from the said fan or blower rearwardly through the shoe 122 and upwardly and rearwardly through and under the chaffing-riddle 123. The bottom of the said casing is also formed with a trans- 90 versely-disposed conveyer-trough 126, which is below the crest 128 of the inclined bottom of the casing, whereby an eddy is formed in the said conveyer-trough, which facilitates the flowing of the grain thereinto from the inclined lower side 129 of the shoe 122. The 95 said conveyer-trough is formed at its center with a depending discharge-spout 130. A conveyer-worm 131 is disposed and mounted for rotation in the said conveyer-trough. The 100 said conveyer-worm comprises two reversely-disposed sections, which operate to move the

grain from the ends of the trough to the center thereof to cause the same to drop through the spout 130. Caps or hoods 132 are supported over the bearings of the conveyer-worm-shaft 5 by brackets 133, which are secured to the inner sides of the said trough. The conveyer-worm-shaft has a pulley 135 at one end thereof which is connected by an endless belt 136 to a pulley 137 on the shaft of the fan 118, and hence the said conveyer-worm is rotated by power communicated thereto from the shaft of said fan.

I will now describe improved means for conveying the grain from the conveyer-trough to sacks or other suitable receptacles. A conveyer-tube 138 is formed at its inner end with an upstanding elbow 139, which is revoluble on the lower end of the spout 130, so that the said conveyer may be turned so that its outer 20 end may be caused to project from either side of the machine, and the said conveyer-tube may be also disposed longitudinally under the center of the machine, where it will be entirely out of the way, as is shown in Fig. 2. When 25 thus disposed, the outer end of the conveyer-tube may be secured, as by a chain 139 and a hook 140. At the outer end of the conveyer-tube is a spout 141, which is disposed at an angle to the said tube and in an inclined position to enable grain discharged thereinto 30 from the tube 138 to flow by gravity outwardly through said spout into a sack or other receptacle. In the conveyer-tube 138 is disposed a conveying-worm 142, which is mounted for rotation, as shown in Fig. 2, and the shaft of which near its inner end is provided with a miter-gear 143. The shaft 131 of the conveyer-worm 132 is provided with a miter-gear 144. A short vertically-disposed shaft 145 is 35 journaled in a bearing 146 in the throat of the spout 130, and said shaft has a miter-gear 147 at its upper end which engages the gear 144 and has a similar gear 148 at its lower end which engages the gear 143. Hence power is

communicated from the conveyer-worm 132 45 to the conveyer-worm 142, as will be understood, and the grain is discharged from the machine through said conveyer-tube 138 and the spout 141 thereof.

Having thus described my invention, I 50 claim—

1. In a machine of the class described, the combination of a shoe, a blower-fan, a casing for the latter having its lower side inclined upwardly to direct the blast into the shoe, a transversely-disposed conveyer-trough formed below the crest of the inclined bottom, between said crest and the shoe, and having a centrally-disposed downwardly-extending discharge-spout, conveyer means for discharging the 60 contents of the trough through said spout, and a swiveled horizontally-disposed extension connected with the lower end of the latter, substantially as set forth.

2. In a machine of the class described, the 65 combination of a shoe, a blower-fan, a casing for the latter having its lower side inclined upwardly to direct the blast into the shoe, a transversely-disposed conveyer-trough formed below the crest of the inclined bottom, between 70 said crest and the shoe, and having a centrally-disposed downwardly-extending discharge-spout, conveyer means for discharging the contents of the trough through said spout, a swiveled horizontally-disposed extension 75 connected with the lower end of the latter, a spiral conveyer in said extension and means for transmitting motion to said spiral conveyer from the conveyer disposed in the transverse trough of the fan-casing.

In testimony that I claim the foregoing as my own I have hereto affixed my signature in the presence of two witnesses.

AUDY A. LOWRY.
